(57) **CLAIM**

The ornamental design for a rolling paper booklet, as shown and described.

DESCRIPTION

FIG. 1 is a front, right isometric view of a rolling paper booklet, showing our new design;

FIG. 2 is a front perspective view of the rolling paper booklet of FIG. 1;

FIG. 3 is a rear perspective view of the rolling paper booklet of FIG. 1;

FIG. 4 is a right side view of the rolling paper booklet of FIG. 1;

FIG. 5 is a left side view of the rolling paper booklet of FIG. 1;

FIG. 6 is a top plan view of the rolling paper booklet of FIG. 1;

FIG. 7 is a bottom plan view of the rolling paper booklet of FIG. 1;

FIG. 8 is a front, right isometric view of another embodiment of a rolling paper booklet, showing our new design;

FIG. 9 is a front perspective view of the rolling paper booklet of FIG. 8;

FIG. 10 is a rear perspective view of the rolling paper booklet of FIG. 8;

FIG. 11 is a right side view of the rolling paper booklet of FIG. 8;

FIG. 12 is a left side view of the rolling paper booklet of FIG. 8;

FIG. 13 is a top plan view of the rolling paper booklet of FIG. 8;

FIG. 14 is a bottom plan view of the rolling paper booklet of FIG. 8;

FIG. 15 is a front, right isometric view of another embodiment of a rolling paper booklet, showing our new design;

FIG. 16 is a front perspective view of the rolling paper booklet of FIG. 15;

FIG. 17 is a rear perspective view of the rolling paper booklet of FIG. 15;

FIG. 18 is a right side view of the rolling paper booklet of FIG. 15;

FIG. 19 is a left side view of the rolling paper booklet of FIG. 15;

FIG. 20 is a top plan view of the rolling paper booklet of FIG. 15;

FIG. 21 is a bottom plan view of the rolling paper booklet of FIG. 15;

FIG. 22 is a front, right isometric view of another embodiment of a rolling paper booklet, showing our new design;

FIG. 23 is a front perspective view of the rolling paper booklet of FIG. 22;

(Continued)

FIG. 24 is a rear perspective view of the rolling paper booklet of FIG. 22;

FIG. 25 is a right side view of the rolling paper booklet of FIG. 22;

FIG. 26 is a left side view of the rolling paper booklet of FIG. 22;

FIG. 27 is a top plan view of the rolling paper booklet of FIG. 22; and,

FIG. 28 is a bottom plan view of the rolling paper booklet of FIG. 22.

The evenly spaced broken lines illustrate perforations, which are environmental subject matter only and form no part of the claimed design. The dash-dot-dash broken lines illustrate portions of the rolling paper booklet that form no part thereof.

1 Claim, 20 Drawing Sheets
